UNITED STATES PATENT OFFICE.

ISADOR LADOFF, OF CLEVELAND, OHIO, ASSIGNOR OF THIRTY ONE-HUNDREDTHS TO PHILIP C. PECK, OF NEW YORK, N. Y.

PENCIL AND APPARATUS FOR PRODUCING THE ARC-LIGHT.

No. 896,397.

Specification of Letters Patent.

Patented Aug. 18, 1908.

Application filed September 23, 1907. Serial No. 394,221.

To all whom it may concern:

Be it known that I, ISADOR LADOFF, a citizen of the United States, and a resident of the city of Cleveland, county of Cuyahoga, 5 and State of Ohio, have invented certain new and useful Improvements in Pencils and Apparatus for Producing the Arc-Light, of which the following is a specification, reference being had to the accompanying drawings.

The objects of my present invention are to attain increased candle power with less expenditure of electrical energy than heretofore, and I attain these objects by the combination, in any apparatus for producing the arc light, of a positive electrode or pencil composed of, or preponderatingly comprising copper and titanium or its compounds, with a negative pencil, or electrode, composed of, or preponderatingly comprising, ferric and titanic materials. The said positive pencil may contain an alloy, or a mechanical combination of copper with titanium, or copper mixed with a compound of 20 titanium, the proportion of titanium to copper being preferably 5 to 75 per cent. of the latter, I having obtained excellent results with pencils composed of copper and as low as from 6 to 8 per centum of titanium, the rule 25 is the same if a compound of titanium, as for instance its oxid, is used with the copper.

The negative pencil may be composed of any alloy, mixture, or other combination, of ferric and titanic material, as for instance an alloy of iron and titanium as per Letters Patent No. 840,634, granted to me January 8, 1907, for improvement in electrical conductor for lighting purposes, or the titanic and ferric compounds may consist of oxids of 35 iron and titanium, or of the oxid of the one and the elemental metal of the other, such pencils, for the purposes of arc lighting, being now well known in the art, require no further description here.

Positive pencils composed of copper have heretofore been used with negatives containing ferric and titanic materials as aforesaid, but my aforesaid combination of titanium

with copper in the positive pencil I believe to be entirely novel, and its results are to greatly increase the candle power, as compared to that derived under similar conditions when a copper positive is used; moreover the consumption of my copper-titanium pencil is not materially more rapid than that of a pencil composed of pure copper. The maximum efficiency and minimum consumption of my said copper titanium positive pencil is attained with a diameter of from five eighths to one inch.

Referring to the drawing, A indicates an arc lamp of usual form and provided with usual feed devices, etc., B my said positive electrode or pencil comprising copper and titanic material, C the negative pencil or electrode comprising ferric and titanic materials. The pencils are of course to be understood as being connected as usual in circuit with a source of electrical energy not shown.

What I claim as new and desire to secure by Letters Patent is the following, viz:

1. In an apparatus for producing the arc light a positive pencil or electrode comprising copper and a titanic material.
2. In an apparatus for producing the arc light a positive pencil or electrode comprising an alloy of copper and titanium.
3. In an apparatus for producing the arc light the combination of a positive pencil or electrode comprising copper and a titanic material, and a negative pencil or electrode comprising ferric and titanic material.
4. In an apparatus for producing the arc light the combination of a positive pencil or electrode comprising an alloy of copper and titanium and a negative pencil or electrode comprising ferric and titanic material.
5. An arc light electrode composed of the alloy of copper and titanium.
6. An arc light electrode containing a preponderance of copper and a titanic material.

ISADOR LADOFF.
